UNITED STATES PATENT OFFICE.

WARREN P. JENNINGS, OF BROOKLYN, NEW YORK, ASSIGNOR OF ONE-HALF
TO ABRAHAM G. JENNINGS, OF SAME PLACE.

MITT-SHAPING MACHINE.

SPECIFICATION forming part of Letters Patent No. 234,286, dated November 9, 1880.

Application filed April 14, 1880. (No model.)

To all whom it may concern:

Be it known that I, WARREN P. JENNINGS, of Brooklyn, in the county of Kings and State of New York, have invented a new and Improved Mitt-Shaping Machine and Process, of which the following is a specification.

My invention relates to an improvement in process of and in apparatus for so forming or shaping knitted or woven mitts as to contract the mitts at the wrist portion and give them a better fit on the hand and wrist. The mitts to be subjected to this treatment are mostly made on bobbinet or warp lace machines.

By the improved machine the mitts are stretched over formers, so that they will be contracted at the desired part, and are then subjected to the action of steam, and then of dry heat for the purpose of permanently setting them to the shape or form they are made to assume.

The invention consists of the mechanism hereinafter described for stretching and contracting the mitts and confining them while undergoing treatment; also, of the means of applying steam and heat to the mitts when used in connection with the other parts of the machine.

The invention also consists of the new lace mitt having the sides and middle meshes contracted between the ends.

In the accompanying drawings, Figure 1 represents a plan view of a machine for applying my improvement in forming mitts. Fig. 2 is a vertical longitudinal section of the same, taken on line *c c* of Fig. 1. Fig. 3 represents a sectional detail of the formers. Fig. 4 represents a mitt before forming; and Fig. 5 represents a mitt formed according to my invention.

Referring to the drawings, A represents a table having an opening, B, about midway in the top. At or near one end a clamp, C, is suspended above or placed on said table. At the opposite end of the table is a sliding plate, D, held between suitable guides *b b*, so that the said plate D will move freely in the direction of the length of the table. The sliding plate D is provided with another suspended or other clamp, E. The clamp C is preferably applied to a stationary plate, e, attached to

the table-top, so that the stationary plate *e* and sliding plate D are at about the same level, and to said plates are attached cloth covers F, which can be folded over the mitts when being formed to protect them from abrasion by the ends of the clamps C E.

G H are the two parts of the former, each being of tapering shape. The part H of the former carries a smooth rod or shank, f, which enters a socket in the part G, as clearly shown in Fig. 3, so that on said shank the parts can slide farther apart or together and yet remain sufficiently united in the machine. The parts G H can also, when off the machine, be entirely disconnected to permit the application and removal of the mitt. One of the parts H, it will be observed, is broader than the other, the one being adapted for the hand of the mitt and the other for the arm portion. Under the open space B in the table A is a coil of steam-pipes, I, or other heating apparatus, and a branch of the coil extends to the end of the table, and is provided with a valve and a flexible tube, J, which carries at its free end a hand-pipe, K, having a nozzle. The sliding plate D is connected with a weight, g, at one end and a treadle, h, or equivalent moving mechanism at the opposite end of the table. By means of the treadle it is drawn toward the stationary clamp C, while the weight draws it in the opposite direction.

Any number of stationary and sliding clamps may be placed side by side on a table sufficiently large to receive them, and the coil I may be arranged to extend the full length of the opening between the clamps, while the flexible tube J and hand-pipe K may be arranged so that the steam can be directed on all the mitts in the machine by the same workman, or several flexible tubes and hand-pipes may be employed, as may be preferred, and the flexible tube may be connected with a separate steam-supply pipe instead of the coil.

The mitt is first drawn over the formers G H, the narrower one being entered from the hand end and the broader one from the arm end, and they are pressed in until the shank f enters the cavity in the part G, care being taken that the space between the two adjacent ends of the formers will fall at about the wrist

portion of the mitt. Thus arranged the mitt, with the formers, is laid on the plates D e, the sliding plate D having been first drawn toward the stationary one. The cloths F are then laid over the mitt and the clamps applied, so as to bear on the cloth and clamp the formers and mitts against the plates e and D. The weight g is now allowed to draw on the sliding plate and clamp, and thereby to dis-
tend the former G H and stretch the mitt so that the strain is borne by the mitt, the tension to which it is subjected serving to contract it between the two parts of the former. By means of the hand-pipe K a jet of steam is now projected on the contracted portion of the mitt from underneath, whereby the fibers are softened, and the mitt at this part assumes more readily a contracted form. The fibers of the mitt are then dried of the moisture deposited on them, and the contraction fixed by the heat from the steam-coil I.

In Fig. 4 is represented a lace mitt before undergoing the forming process. It will be observed that the sides are nearly straight lines, having none of the curves characteristic of the corresponding parts of the hand and wrist. In Fig. 5 is represented the same mitt after undergoing the above-described treatment, showing a contracted portion correspond-
ing to the wrist and the part of the hand next to the wrist.

The mitt thus produced, it will be seen, has its sides bent inward and the meshes laterally contracted, thereby obtaining the desired form without reducing the number of the meshes at the contracted portion.

I claim—

1. The process of shaping lace mitts, which consists in first stretching the mitts length-
wise, and thereby contracting them at the de-
sired point, and in then subjecting them first to the direct action of steam, and next to

heat, for the purpose of setting the fibers to the desired form, substantially as herein shown and described.

2. In a machine for elongating and laterally contracting mitts, the combination and arrangement of two clamps, of which one is sliding, with a sectional former adapted to be placed within the mitts, substantially as herein shown and described.

3. The combination of the stationary plate e, and its clamp C, with the sliding plate D, and its clamp E, and with the former G H, substantially as herein shown and described.

4. The table A, provided with the opening B, and the coil I, in combination with the clamps C E and former G H, for holding the mitt to be operated upon, substantially as de-
scribed.

5. In combination with the table A, clamps or holders, and the former for holding the mitts, the flexible tube J, and hand-pipe K, connected with a steam-supply, substantially as described.

6. The automatic former composed of sec-
tions G H, which are connected together by a smooth shank, f, loosely inserted in one of the sections, a space being left between the sec-
tions, all arranged to allow the sections to be drawn apart or contracted automatically by the tension of the fabric that surrounds them, substantially as herein shown and described.

7. As a new article of manufacture, the seamless lace mitt having the sides and mid-
dle meshes contracted laterally between its ends without reducing the number of meshes at its contracted parts, substantially as shown and described.

WARREN P. JENNINGS.
